THE COLUMBIA PLANOGRAPH CO., WASHINGTON, D. C.

UNITED STATES PATENT OFFICE.

HANS K. A. KARLSEN, OF OMAHA, NEBRASKA, ASSIGNOR OF ONE-HALF TO ANDREW J. ANDERSEN, OF UTE, IOWA.

POWER HAMMERING APPARATUS.

1,181,015.

Specification of Letters Patent. Patented Apr. 25, 1916.

Application filed July 6, 1915. Serial No. 38,191.

To all whom it may concern:

Be it known that I, HANS K. A. KARLSEN, a citizen of Denmark, residing at Omaha, in the county of Douglas, and State of Nebraska, have invented certain new and useful Improvements in Power Hammering Apparatus, of which the following is a specification.

The apparatus of the present invention is 10 designed as an improvement in power or die-hammering machines, and the particular feature of such improvement relates to adjusting means for the hammer actuating member such that the stroke, and consequently 15 the blow of the hammer, is regulated according to the effect desired or the character of work operated upon.

A further object in view is to provide 20 movable guide means for the hammer member for the purpose of obtaining a reversal of the hammer member to bring into play a different style of peen; such movement of the guide means being advantageous in facilitating the change or replacement of the 25 anvil or die elements, and the interposition of the work in place for operation thereupon.

These and such other objects as may hereinafter appear are attained by the novel 30 construction, combination, and arrangement of parts to be hereinafter specifically described and claimed.

Reference will now be had to the accompanying drawings forming a part of this 35 specification, wherein:

Figure 1 is a side elevation of a device 40 constructed in accordance with my invention. Fig. 2 is a top plan view thereof, parts being broken away and shown in section to disclose the clutch elements more clearly. Fig. 3 is an elevation of the opposite side of 45 the apparatus to that disclosed by Fig. 1, parts being broken away and in section, and the hammer member being shown in its reversed position for coöperation with a different anvil. Fig. 4 is a vertical sectional view taken about on the plane indicated by the line 4—4 of Fig. 3, looking in the direction of the arrows. Fig. 5 is a detail view 50 of the fulcrum block and adjusting means therefor. Fig. 6 is a fragmentary sectional view taken about on the line 6—6 of Fig. 1 looking in the direction of the arrows; and Fig. 7 is a vertical sectional view on the line 55 7—7 of Fig. 1, showing more clearly the

locking means for the operating member of the hammer guide sleeve.

Throughout the following detail description, and on the several figures of the drawings, similar parts are referred to by like 60 reference characters.

Referring to the drawings by numerals, 1 designates a standard or support fixed to the surface upon which it rests in any desired manner and having an offstanding arm 65 2 integral therewith. Upon one face of this support adjacent its upper extremity is formed a dovetailed guide groove 3 adapted to slidably receive a fulcrum block 4 shown most clearly in Fig. 5 of the drawing. The said block is formed with a dovetailed plate 5, at one side, which is seated in the groove 3 before mentioned and said block on its upper end is also formed with transverse bearing 6 to receive the trunnions 70 7 of a carrying plate 8 to which is fixed a flexible hammer actuating member or spring 9. Bearing plates 10 are fixed to the block 4 over the trunnions aforesaid to hold the actuating member in position upon the 75 block 4. The rear end of the spring has connected thereto a vertically disposed connecting rod 11 secured at its lower end to an eccentric strap 12 mounted upon an eccentric disk 13 which is adapted to impart vertical reciprocatory movement to said connecting rod. The eccentric shaft 14 carries at one end a loose pulley 15 adapted to be driven by a belt 16 and from a suitable source of power, and secured to the shaft is 80 a clutch member comprising the sleeve 17 and the clutch drum 18 coacting with the pulley 15 which constitutes the coöperating clutch member. To the sleeve 17 is operatively connected the spring actuated treadle 85 19 which passes around the hammer machine and is pivoted at opposite sides of the support 1 as indicated at 20. Located in advance of the support 1 is a base 21 at the top of which is removably disposed the anvil 90 22. With this anvil the hammer member 23 is adapted to coact, said hammer being of any well known type and configuration, having formed thereon a lateral projection or stud 24 which is loosely secured in the 95 slotted extremity 9' of the hammer actuating spring 9. The hammer 23, it will be understood, is, therefore, loosely connected to said spring and is held in proper coöperating position with respect to the anvil 22 by 100 105 110 115 116

means of the guiding sleeve 25. This sleeve is cylindrical in shape and formed with a lateral projection 26 rotatably received in the outer extremity of the support arm 2. 5 The hammer 23 is loosely held in said sleeve by means of the spaced plates 27 secured by bolts 28 to one face of the sleeve so as to hold the hammer in vertical position for reciprocation in said sleeve. It will, furthermore, be apparent that the hammer is preferably constructed with different types of peens at opposite extremities for operating upon different characters of articles.

One of the main features of this apparatus 15 is incidental to the disposition of the sleeve 25 on the arm 2 so that said sleeve is capable of being rotated to reverse the hammer, as shown in Fig. 2 for bringing into position the peen at the opposite end, which peen is 20 adapted to coact with a flat shaped anvil 22' replacing the type shown in Fig. 1. To enable such reversal action, a lever or handle 29 is pivotally mounted upon the lateral projection 6, as shown in Figs. 1, 2 and 3, at 25 29', said handle normally lying at right angles to said projection and contiguous to the side of the arm 2, which arm is provided with a locking member 30 with which the handle is adapted to be interlocked for holding the hammer in its normal vertical position. To obtain the reversal, the handle 29 is disengaged from the member 30 by lateral movement thereof whereupon the head or 30 guide 25 is rotated in the arm 2 until the opposite extremity or peen of said hammer is brought into position whereupon the handle is again engaged with the locking member 30. It will be obvious to those skilled in the art to which this invention refers that this serves 40 also a further advantageous function in that it facilitates the removal of the work or disposition of said work upon the anvil beneath the hammer irrespective of the position at which the actuating member 9 for said hammer may be holding the latter. Furthermore, by reason of the slotting of the extremity of the actuating member 9 even during reciprocation of the hammer, it is capable of being rotated out of its path of normal movement with respect to the anvil, 45 eliminating also likelihood of injury to the operator in adjusting the work in proper position.

Another important feature of this apparatus 55 is the provision of adjusting means for the fulcrum of the hammer actuating member 9 so that the distance or throw of this member may readily be controlled and necessarily the blow with which it operates upon the 60 object worked upon. To accomplish this adjustment the block 4, as will be observed in Figs. 4 and 5, is formed with a recess 31 in the plate side 5 thereof and in said recess is seated a disk or cam 32 eccentrically carried by a shaft 33 extending through the up-

per portion of the support 1 and carrying at its outer extremity an adjusting or operating lever 34. At this side of the standard 1 is provided a notched segment 35 with which the lever 34 co-operates to hold the fulcrum 70 block 4 at adjusted positions. Movement of the handle 34 obviously will cause the disk or cam 32 to raise or lower the fulcrum block and consequently increase or decrease the distance of the hammer 23 from the anvil 75 22. By reason of the resiliency of the actuating member 9, the vibrations imparted thereto by the driving means 11 will cause a greater or less effect with respect to the blows imparted by the hammer upon the 80 work according to the distance which the hammer has to move in its reciprocation in the guide means therefor.

It is needless to mention the advantages inherent to a machine which is capable of 85 being adjusted during the operation thereof since it will readily be appreciated that much time is saved in carrying out the operations where the driving mechanism does not have to be stopped and yet permit effect 90 of the operating elements to be regulated according to the character of work which is to be performed or the effect it is to have upon said work.

Having thus described my invention, what 95 I claim as new is:

1. In a device of the class described, the combination of a support, a hammer, an actuating member fulcrumed on said support and to which the hammer is connected, 100 means for regulating the throw of the hammer comprising a fulcrum block to which the actuating member is pivotally connected, guide means for said block, and rotatable means interlocked with said block to raise or 105 lower the same on the support.

2. In a device of the class described, the combination of a support, a hammer, an actuating member fulcrumed on said support and to which the hammer is connected, and 110 means for regulating the throw of the hammer comprising a fulcrum block slidably mounted on the support for movement in a vertical plane and pivotally carrying the actuating member, the support being recessed 115 to receive the block and guide its sliding movements, a revoluble cam co-operating with the block, and means operable during the actuation of the hammer for rotating the cam to raise or lower the block on the support.

3. In a device of the class described, the combination of a support, a hammer, an actuating member fulcrumed on said support and to which the hammer is connected, and 125 means for regulating the throw of the hammer comprising a fulcrum block to which the actuating member is pivotally connected, the support having a lateral groove in which the block is movable, said block also having 130

a recess therein, rotatable means seated in the recess of said block to raise or lower the same on the support, and means at the opposite side of the support for positively holding the rotatable means and the block at adjusted positions.

4. In a device of the class described, the combination of a support, a hammer, an actuating member fulcrumed on said support and to which the hammer is connected, and means for regulating the throw of the hammer comprising a fulcrum block disposed at one side of the support and to which the actuating member is pivotally connected, means movably connecting the block to the support, an eccentric cam on which said block is mounted, manual means at the other side of the support for adjusting the cam to raise or lower the block, a shaft connecting the manual means and the cam aforesaid, and means engageable with the said shaft to hold the block at adjusted positions.

5. In a device of the class described, the combination of a support, a hammer, an actuating member fulcrumed on said support and to which the hammer is connected, and means for regulating the throw of the hammer comprising a fulcrum block to which the actuating member is pivotally connected, means connecting the block to the support, an eccentric cam on which said block is mounted, a lever for rotating the cam to raise and lower the block, and locking means engageable with the lever for holding it at adjusted positions.

6. In a device of the class described, the combination of a support, an actuating member mounted thereupon, a hammer device connected to the actuating member and having a plurality of peens, and revolute guide means connecting said hammer to the support whereby the hammer may be reversed to bring the respective peens into operative position.

7. In a device of the class described, the

combination with a support, an actuating member fulcrumed thereon, means for operating the actuating member, a hammer connected to the latter, and revolute means reciprocatingly connecting the hammer to the support.

8. In a device of the class described, the combination with a support, an actuating member fulcrumed thereon, means for operating the actuating member, a hammer connected to the latter, revolute means reciprocatingly connecting the hammer to the support, and means for rotating said revolute means to displace the hammer from its normal plane of movement.

9. In a device of the class described, the combination with a support, an actuating member fulcrumed thereon, means for operating the actuating member, a hammer connected to the latter, a guide sleeve for said hammer revolutely carried by the support, and a lever for rotating the sleeve and hammer.

10. In a device of the class described, the combination with a support, an actuating member fulcrumed thereon, means for operating the actuating member, a hammer pivotally connected to the actuating member, and means on the support for holding the hammer in reciprocatory position.

11. In a device of the class described, the combination with a support, an actuating member fulcrumed thereon, means for operating the actuating member, a hammer to which the actuating member is loosely connected, a guide sleeve carried by said support and co-operating with the hammer to hold the same in position for reciprocation, a lever fixed to said sleeve, and means on said support coacting with the lever for holding the hammer in its normal reciprocating position.

In testimony whereof I affix my signature.

HANS K. A. KARLSEN.
